UNITED STATES PATENT OFFICE.

GILBERT CRAIN PHLEGER, OF SPRINGFIELD, OHIO, ASSIGNOR TO VIRDIE P. PHLEGER,
OF SPRINGFIELD, OHIO.

WRENCH.

Application filed April 8, 1922. Serial No. 550,768.

To all whom it may concern:

Be it known that I, GILBERT C. PHLEGER, a citizen of the United States, residing at Springfield, in the county of Clark and 5 State of Ohio, have invented certain new and useful Improvements in Wrenches, of which the following is a specification.

This invention relates to improvements in wrenches.

10 The primary object of the invention is the provision of a wrench which may be quickly adjusted, in order that the same may be selectively used for gripping plane or arcuate surfaced articles.

15 A further object of the invention is the provision of a wrench including fixed and sliding jaw structures, and in which the sliding jaw structure may be quickly adjusted with respect to the fixed jaw structure.

20 A further object of the invention is the provision of a wrench jaw primarily adapted for use in connection with the gripping of plane surfaced articles, but which includes a novel arrangement so that the 25 wrench jaw may have an auxiliary gripping element extended outwardly with respect to the article gripping face of said jaw, in order that said auxiliary gripping member may be utilized in connection with said jaw to engage round surfaced articles, such as 30 pipes.

A further object of the invention is the provision of a wrench embodying the above mentioned characteristics, so that the article 35 engaging surfaces of the jaws upon said wrench may be normally positioned in parallel relation, for the gripping of polygonal shaped articles, such as nuts; said wrench furthermore including improved 40 auxiliary means for riding outwardly of the plane of said article engaging surfaces of the jaws, and whereby the wrench may be utilized for gripping pipes and the like, much in the same manner as the ordinary 45 pipe wrench.

Other objects and advantages will be apparent during the course of the following detailed description.

In the accompanying drawings, forming 50 a part of this specification, and wherein similar reference characters designate corresponding parts throughout the several views,

Figure 1 is a fragmentary side elevation,

partly in section, showing the cooperating 55 relation of the wrench parts.

Figure 2 is a fragmentary side elevation of portions of the improved wrench, showing the same in a differently adjusted position than that illustrated in Figure 1. 60

Figure 3 is a side elevation of the head portion of said wrench, showing the fixed and sliding jaws thereof in abutting relation.

Figure 4 is an edge elevation of the improved wrench structure as illustrated in Figure 3.

Figure 5 is a transverse cross sectional view taken on the line 5—5 of Figure 1.

Figure 6 is a transverse cross sectional 70 view taken on the line 6—6 of Figure 1.

Figure 7 is a cross sectional view taken on the line 7—7 of Figure 3.

In the drawings, wherein for the purpose of illustration is shown the preferred embodiment of my invention, the letter A designates the improved quick adjusting wrench, which comprises a supporting shank 10; fixed jaw 11; sliding jaw 12; auxiliary grip devices 13 and 14 for the fixed and sliding jaws respectively; and locking arrangement 15 for connection of the sliding jaw 12 in different positions upon the shank 10. 75

The shank 10 is substantially rectangular 80 in cross section, and of uniform cross section throughout the length thereof. The upper end thereof is provided with the fixed jaw 11, preferably as an integral part thereof, and arranged in T-shaped manner 85 thereon, so that one side 17 extends laterally of the shank 10 to have the lower face 18 thereof for acting as an article gripping surface, this face or surface 18 being preferably arranged in a plane at right angles to the extension of the shank 10, much in the same manner as the construction of the ordinary monkey wrench.

As can readily be seen from Figure 4 of the drawings, the head or fixed jaw 11 is 100 of greater width than the width of the shank 10, extending outwardly upon both sides thereof, one of the extending sides being, in fact, a cover 20 which is secured as by rivets or other elements 21 to the head portion 22 of the fixed jaw 11, so that the auxiliary grip 13 to be subsequently described may be properly housed in the said 105

jaw 11. The opposite end of the shank 10 is preferably provided with a knob 25 extending laterally thereof, whereby the sliding jaw 12 may be properly affixed to said shank 10 against liability of accidental displacement. The sliding jaw structure 12 is relatively longer than the jaw structure 11, since the same is adapted for housing both the auxiliary grip means 14 and the locking means 15. This jaw 12 preferably comprises a body portion 29 having the rectangular shaped groove 30 extending longitudinally thereof and adapted for snug sliding reception of the shank 10 therein. A cover 31 is provided for clamping over that side of the body portion 29 in which the groove 30 is formed, in order that the groove 30 may form a pocket in which the shank 10 may slide. This cover 31 may be maintained in proper relation upon the body portion 29 as by rivets 32. A portion 35 of the sliding jaw structure 12 extends laterally of the shank 10 and in operative relation to the laterally extending portion 17 of the fixed jaw structure 11. An article engaging face 36 is provided upon this portion 35, which lies in a plane substantially at right angles to the longitudinal extension of the shank 10. Thus, the article engaging faces 18 and 36 of the fixed and sliding jaw structures respectively, are in parallel relation, and in fact, so related as to be in facing cooperation for receiving nuts, pipes and other articles to be gripped.

Referring to the locking means 15, the same includes a wedge shaped member 40 slideable in a groove 41 formed inwardly from the same side of the sliding jaw body 29, in which the shank groove 30 is formed, this groove 41 in fact, defining a taper surface against which the wedge 40 operates, so that one side 42 of the wedge 40 is normally in parallel relation with a marginal edge of the shank 10. A spring 43, preferably of the compressible type, is disposed within a pocket 44 of the sliding jaw body 29, one end of said spring engaging the enlarged edge of the wedge member 40, whereby the latter is normally forced upwardly in its groove 41, so that its surface 42 is forced into snug engagement against the shank 10. Thus, it can be seen that this action of the wedge 40 against the shank 10 will have a tendency to firmly lock the sliding jaw structure 12 to the shank 10. A pocket or recess 46 is formed inwardly from the rear of the sliding jaw 12, having a lever 47 pivotally connected as by a rivet 48 to the body and cover portions of the sliding jaw structure 12, so that an inside end 49 of the lever 47 is disposed adjacent the reduced end 50 of the wedge member 40. This reduced end 50 of the wedge member 40 normally extends into the pocket 46, so that when the lever 47 is rocked by an oper-

ator, the inside edge 49 thereof may engage the end 50 of said wedge, so that the same may be depressed against the action of the spring 46, to release the same from binding engagement against the shank. The operation of this locking mechanism 15 is obvious from the construction illustrated in Figure 1 of the drawings.

The auxiliary gripping device 13 comprises a grip member 52 which is pivotally connected as by a pin 53 within a recess 54 formed in the head portion 22 of the fixed jaw 11, said recess 54 preferably being open upon the face 18 of the jaw structure 11, so that the member 52 may be rocked outwardly from the plane defined by the face 18. The marginal edge of the grip member 52 is preferably provided with a series of teeth 55, which when the member 52 is snugly within its pocket recess 54 will be disposed inwardly of the face 18, so that they will not interfere with any article being gripped upon the face 18. However, when the member 52 is rocked outwardly from the fixed portion 17 of the jaw 11, the teeth 55 will be extended outwardly of the same. Since the pin 53 pivots the member 52 upon an end thereof adjacent the shank 10, it can be seen that the forward end of the member 52 is capable of the greatest extension outwardly from the face 18. Since the teeth 55 are in rack formation, it is obvious that the plane in which they lie will define an article engaging portion or surface which is disposed in a plane at an acute angle with respect to the plane defined by the article engaging surface 18. A lug 57 operating within a groove 58 limits the extension of the grip member 52 from the jaw 11. A spring 59, preferably of the flat type, is affixed in the pocket or recess 54 of the jaw head portion 22, so that the forward end thereof engages a pin 60 affixed in the auxiliary grip member 52, said spring 59 being normally under a tension to maintain the grip member 52 in the pocket 54, so that the teeth 55 thereof lie inwardly from the article gripping surface 18. A cam lever 63 is pivoted in the pocket 54, as by pins 65, which extend transversely of the jaw structure 11. A knob 66 is formed upon the outer end of one of the pins 65 and extends from the outside surface of the jaw structure 11, for manual engagement, whereby when the same is oscillated, the lever 63 may be thrown to exert a cam action upon the grip member 52 for forcing the same outwardly from the jaw 11, as hereinbefore described. This lever 63 co-acts against an abrupt shoulder 66, formed in the member 52, whereby said grip member 52 when in its extended position may be securely braced against the lever 63 for article gripping purposes.

Referring to the auxiliary gripping de-

vice 14 as carried upon the sliding jaw structure 12, the same includes a grip member 70, slidably disposed within a pocket 71 formed inwardly of the sliding jaw body 29, from the article gripping face 36 thereof. The lower surface 72 of this pocket 71 is inclined, in converging relation, with respect to the article gripping surface 36, so that said pocket decreases in depth from 10 the outer end of the jaw portion 35 towards the shank groove 30 therein. The grip member 70 is provided with a series of teeth 73 thereon, arranged in rack like formation. The lower surface or marginal 15 edge 74 of this grip member 70 which is opposite to the plane in which the teeth 73 lie is formed in tapering relation with respect to the plane in which said teeth 73 are disposed, said surface 74, in fact, being provided for sliding engagement upon 20 the pocket surface 72 and having guide flanges 82^a thereon operating in lateral grooves 83^a. A flexible spring 76, preferably of the flat type, is carried in a groove 25 77 of the sliding jaw 12, normally having an end thereof cooperating against the grip member 70 to force the same away from the shank receiving groove 30, substantially as is illustrated in Figure 1 of the drawings. 30 When the gripping member 70 is in this position, the teeth 73 lie inwardly from the plane defined by the article engaging face 36 of the wrench structure 12, so that when said sliding jaw structure 12 engages a 35 nut or pipe, the teeth 73 will in no wise interfere with such action. In order to effect a manual operation of the auxiliary grip member 70, a pin 79 is oscillatively mounted transversely of the sliding jaw 12 and in the laterally extending portion 35 thereof, said pin 79 having a knob portion 80 thereon, which extends from a side of the jaw structure 12 altogether similar to the extension of the knob 66 above described. A stem 81 is radially disposed upon the pin 79 adapted for engagement against a shoulder 82 formed inwardly from the inclined surface 74, so that upon oscillation 45 of said pin 79, the stem 81 thereof will engage said shoulder 82 for sliding the member 70 upwardly upon the inclined surface 72, and whereby the teeth 73 may be extended outwardly of the plane defined by the article engaging surface 36, and substantially as is illustrated in Figure 2 of the drawings. 55

In operation, for the adjusting of polygonal shaped articles, such as nuts, bolts heads, and for the holding of other plane surfaced articles, the auxiliary gripping devices 13 and 14 will be so arranged in their respective jaw structures that the teeth 55 and 73 thereof will not extend from the article engaging surfaces 18 and 36. In this 60 manner, the fixed sliding jaw structure 12

may be adjusted upon the shank 10, so that the surfaces 18 and 36 may engage the sides of a nut or other article, having relatively flat surfaces, and upon releasing of said lever 47, the sliding jaw structure 12 will lock, 70 whereby the wrench A may be used for adjusting purposes. On the other hand, if it is desired to hold pipes, or adjust couplings or other articles having arcuate surfaces, it will be desired to use the wrench A much 75 in the same manner as the ordinary pipe wrench is used. To this end, the auxiliary gripping members 52 and 70 are so adjusted in their respective jaw structures 11 and 12 that the teeth 55 and 73 thereof will be extended from the article engaging surfaces 18 and 36. In this position, it is to be noted 80 that the plane in which the teeth 55 lie is at an acute angle to the longitudinal extension of the shank 10. On the other hand, the plane in which the teeth 73 lie is substantially at right angles to the longitudinal extension of the shank 10. Thus, a pipe or other similar article may be gripped by adjusting the jaw 12 so that the same is engaged by the teeth 55 and 73, and upon locking of the sliding jaw structure 12 upon the shank 10 as above described, the pipe or other article may be held or adjusted as 85 desired.

From the foregoing, it can be seen that a wrench has been provided, which is an extremely useful device, in that the same can be quickly and conveniently adjusted. The toothed gripping members 52 and 70 will 90 hold their extended positions notwithstanding the springs 59 and 76 co-acting thereon, since said springs are only provided for return of their grip members when an operator has properly adjusted the knobs 66 and 80. Thus, the wrench may be utilized 95 for various purposes. It is to be noted that lateral extensions 90 and 91 are provided upon the fixed and sliding jaws respectively, 100 which extend outwardly thereon opposite to the article engaging portions above described, said portions 90 and 91 having the surfaces 92 and 93 respectively. 105

Various changes in the shape, size and arrangement of parts may be made to the form of the invention herein shown and described, without departing from the spirit of the invention or the scope of the claims. 110

I claim:

1. A wrench comprising a shank, a fixed jaw mounted upon said shank, a sliding jaw mounted upon said shank including an article engaging extension, and an extension disposed opposite upon said shank with respect to said article engaging extension, said second mentioned extension having a pocket therein provided with a tapered surface facing an edge of said shank, a wedge shaped locking member disposed in the pocket of said sliding jaw for operation against the 120

tapered surface therein, a spring normally forcing said wedge member into engagement with said tapered surface, whereby the wedge member is locked into engagement with said shank, and a lever oscillatively mounted within said pocket at substantially right angles to the wedge member to have an end thereof bearing against said wedge, whereby the lever may be manually moved for moving the wedge member out of locking engagement with said shank.

2. A wrench comprising a shank, fixed and movable jaws cooperatively mounted upon said shank, one of said jaws having a recess disposed inwardly from the working face thereof and having a pocket leading from the recess an auxiliary gripping member within said recess and pivotally mounted at one end, a spring cooperating with said auxiliary gripping member to normally urge the same inwardly of the outer surface of the jaw in which it is positioned, a lug carried by said auxiliary gripping member for operating against said jaw in which it is positioned to limit the amplitude of outward movement of the same, and an operating pin rotatably carried by the jaw and including a radially extending arm normally seated in

the pocket and adapted for operating against said auxiliary member to cause movement of said auxiliary jaw to an extended position when the pin is rotated in one direction.

3. A wrench comprising a shank, a fixed jaw on said shank, a jaw slidable on said shank providing an article engaging surface having a recess inwardly thereof, the bottom of said recess providing a surface inclined at an acute angle to the plane of the article engaging surface of said jaw, an auxiliary gripping member provided with teeth thereon slidably mounted on the inclined surface of said slidable jaw, a spring carried by the sliding jaw and engaging an end of said auxiliary member to normally urge the same into retracted relation with respect to the jaw on which it is positioned, and an operating pin rotatably mounted in the jaw and having a lug extension engaging the auxiliary gripping member so that the auxiliary grip member may be moved longitudinally and into extended relation from said jaw recess against the action of the spring when the pin is rotated in one direction.

GILBERT CRAIN PHLEGER.
